STAND-BY REFRIGERATION SYSTEM

James W. Martin, St. Petersburg, Fla., assignor,
by mesne assignments, to The Broquinda Corporation,
St. Petersburg, Fla., a corporation of Florida

Application January 20, 1947, Serial No. 723,158

2 Claims. (Cl. 62—13)

1

This invention relates to improvements in refrigerating systems as applied to vehicles.

This invention comprises a system of refrigeration for use on mobile refrigerators such as refrigerated trucks, railway cars, LCL (less than carload lots) containers and the like. The invention is concerned with such systems constructed for the use of a solid primary refrigerant such as water ice, solid carbon dioxide ice and the like. Refrigerating systems using such a primary source of refrigeration frequently include a closed liquid circulatory system in which the liquid acts as a secondary refrigerant, circulating between the primary refrigerant and the space to be refrigerated to abstract the heat from that space and return it to the primary source where it is dissipated. This type of system has found extensive use in mobile refrigerating systems notwithstanding the fact that it is a relatively expensive type of refrigeration in operation because of the many advantages incident to its use. Because of this high cost of operation efforts have been made to provide a system and method of refrigerating the mobile units during standby periods, for example, during the night when the mobile units are inactive. It is well understood in this art that the usual stationary refrigerating systems as ammonia plants, for example, are relatively inexpensive to operate. It is commonly possible to attain refrigeration at a cost as low as a dollar per ton of refrigeration whereas refrigeration by solid carbon dioxide costs about twenty dollars per ton of refrigeration.

The main object of this invention, therefore, is to provide a system wherein, during standby periods, such fixed sources of mechanical refrigeration are employed to maintain the mobile refrigerator units at the proper low temperatures, with the result that during standby periods the cost of refrigeration is greatly reduced.

A more specific object of the invention is to provide a simple mechanism by means of which the refrigerating system with which the mobile refrigerator is equipped is adapted for connection to a fixed mechanical refrigerating system.

Other and more detailed objects of the invention will be apparent from the following description of the embodiment thereof illustrated in the attached drawing.

In the accompanying drawing the single figure is a diagrammatic and schematic illustration of the subject matter of this invention showing some parts in cross section.

A refrigerator truck has been selected for the

purpose of illustrating the invention. The truck includes a body 10 suitably insulated to form a closed space to be refrigerated. This space is refrigerated during the active periods by means of solid carbon dioxide and the like. A container 11, preferably of metal, forms a compartment in which the blocks 15 of solid carbon dioxide are placed so as to rest on the bottom wall of the container 11 in heat conductive relation therewith. Surrounding the container 11 in spaced relation with respect thereto is a housing 12 which may be of a heat conducting material without a heat insulating covering or which may be enclosed in a heat insulating covering, not shown, depending on whether or not it is desired to absorb heat at this point from the space to be refrigerated. The containers 11 and 12 are nested, as shown, in spaced relation and are connected together at their peripheries to form a fluid tight joint with the result that the closed space 13 results. The inner container 11 is open at the top so that the solid carbon dioxide can be charged thereto. A removable heat insulating cover 14 is provided, equipped if desired, with some means (not shown) to permit the escape of carbon dioxide gas to the atmosphere.

A heat absorbing coil or plate 16 is provided having connections to the space 13 at the points 17 and 18, as shown. The space within the coil 16 and the space 13 are filled with a suitable liquid which will circulate by thermosyphonic action from the space 13 to and through the coil 16 and back to the space 13. The liquid in the space 13 will be cooled by conductive heat exchange with the ice 15 through the conductive wall 11. The cool liquid will move to the bottom of the space 13 and enter the coil 16 at its inlet 17. As it moves through the coil it absorbs heat from the space being refrigerated and in heated condition is discharged from the coil 16 through its exit end 18 into the space 13. Thus by natural circulation the liquid secondary refrigerant absorbs heat in the space being refrigerated and carries it to the primary refrigerant where it does work in subliming it or melting it.

This part of the system will be recognized by those skilled in the art as one well known type of refrigerating system now in common use in various forms.

In the operation of a system of this type as previously mentioned, it costs about twenty dollars per ton of refrigeration to maintain the refrigerated space suitable for the storage and transportation of perishable food products. The

refrigerated vehicles are commonly inactive for a large portion of each day and therefore any system which would make it possible to keep the refrigerated space at a safe low temperature during these periods at a lower cost would be of considerable utility. As the cost of refrigeration by means of fixed mechanical refrigerating systems is relatively much lower, the use of such systems during the inactive periods of the vehicle would be desirable. The warehouse or distributing point from which such vehicles are dispatched being the main storage point for the perishable products to be transported are commonly equipped with mechanical refrigerating apparatus. In accordance with this invention, advantage is taken of all these factors.

As illustrated in the drawing, the cooling coil 16 is provided with a cooling coil 19 concentric therewith, the ends 20 and 22 of which extend exteriorly of the coil 16 and are provided with the valves 21 and 23 respectively. At 26 is diagrammatically illustrated any available source of fixed refrigeration. This system, for example, may be an ammonia plant or other common type of mechanical refrigerating plant. Illustrated in the drawings at 24 and 25 are any suitable means as, for example, flexible pipes by means of which the ammonia circulatory system of the refrigerating source 26 can be attached to the ends 20 and 22 of the inner coil 19.

When the truck 10 returns to the warehouse to stand by until morning the source 26 is connected to the coil 19 and valves 21 and 23 are opened. With the source 26 in operation, refrigerated ammonia at the proper temperature is caused to circulate in the coil 19. By heat transfer through the wall of the coil 19 the secondary refrigerant in the coil 16 is set in circulatory movement that is, convection currents are set up in planes substantially at right angles to the length of the coil 16. It is obvious therefore that the secondary refrigerant in the coil 16 absorbs heat from the space of the body 13 and transfers it to the ammonia in the coil 19. Thus, by this simple mechanism the refrigeration of the apparatus 10 is taken over by the mechanical refrigerating source. An improved and unobvious advantage of this system is that the secondary refrigerant in the coil 16 does not move into, through and from the space 13 but takes place, as explained, in planes at right angles to the coil 16. The result is that the solid carbon dioxide 15 does not do any work and therefore in a large measure is preserved for use the next day when the vehicle goes back into active use. Only so much refrigeration is lost by the solid carbon dioxide as is represented by the leakage of heat to it. The stationary secondary refrigerant in the space 13 acts as an insulating layer and if the outer container 12 is enclosed within an insulating

covering the blocks 15 are reasonably well protected against the entry of heat. Thus, the combination herein disclosed acts simultaneously to provide standby refrigeration at relatively low cost and by its peculiar manner of functioning short circuits the circulatory system of which the coil 16 is a part so that the solid carbon dioxide is preserved for future use.

It will be apparent to those skilled in the art that the subject matter of this invention has been disclosed in its broad outline without special reference to detailed mechanical features which would naturally be used in applying this subject matter to an actual installation. The connection of the source 16 to the coil 19 can be greatly facilitated by the use of suitable coupling devices which permit connecting up and disconnecting the parts quickly. It is likewise apparent that suitable forms of automatic thermostatic control and other common accessories can be used. I do not therefore desire to be limited to the system as illustrated but only as required by the appended claims.

What is claimed is:

- 25 1. In a refrigerating system for a heat insulated housing, a closed circulatory liquid containing system in said housing including a receptacle for ice, a chamber about said receptacle connected to the ends of said system at vertically spaced points whereby the liquid moves longitudinally thereof under thermosyphonic action to refrigerate the interior of said housing, a conduit immersed in the liquid in said system and means for circulating a refrigerating fluid 35 through said conduit.
2. An apparatus for effecting standby refrigeration of a mobile refrigerating unit having a heat insulated housing forming the compartment to be refrigerated, comprising a liquid containing cooling coil in said housing including a receptacle for ice for cooling said liquid by conductive heat exchange and a cooling coil within and immersed in the liquid of said first cooling coil and adapted to be connected to an external 45 source of refrigeration.
